UMBRELLA

Frank Kahn, Philadelphia, Pa.

Application July 21, 1931, Serial No. 552,130

21 Claims. (Cl. 135—46)

This invention relates to an umbrella or sun-shade, and relates more particularly to an umbrella having a flexible joint in the upper portion of the stick.

5 When a horizontal gust of wind strikes an umbrella and exerts a lateral pressure on the outer convex covered surface while the handle of the stick is held in the hand of the user, a turning moment about the handle is exerted by the 10 wind. When the umbrella is deflected from its normal position by the turning moment of the wind, so that the wind gains access to the inner concave surface of the cover, a relatively tremendous force is exerted by the wind, tending to tear 15 the umbrella from the grasp of the user or to turn it inside out. This action takes place so rapidly when a sudden gust of wind arises that the umbrella frame may be broken or the cover may be torn before the umbrella can be steadied. 20 My invention, while permitting the umbrella to be carried in the ordinary manner, to prevent rain or sunshine from striking the person, utilizes the force of the wind itself to prevent a sudden gust from reaching the inner concave surface of 25 the cover, and thus effectually prevents the umbrella from being blown inside out.

An object of the invention is to provide a construction for an umbrella which will prevent or minimize the possibility of the umbrella being 30 blown inside out or torn from the grasp of the person holding the umbrella, by the wind.

With this object in view my invention embodies an umbrella frame and cover supported on a short stick which interfits with an extension of 35 the stick utilized as a handle for the umbrella, having a self-aligning resilient universal joint between the stick and the extension handle. The joint is provided so that as a gust of wind strikes the umbrella horizontally the windward side of 40 the cover will move inward toward the handle, thus reducing the turning moment and rendering the umbrella easier to handle as well as shielding the bearer more effectively from the wind and windblown rain.

45 A further object is to provide an improved device of the character described, of simple, cheap, and efficient construction having a maximum efficiency.

With these and other objects in view, my invention consists in the following details of construction and combination of parts, as will be more fully understood from the following specification and drawing, in which:

50 Figure 1 is a diagrammatic view of my umbrella showing the relative position of the flexing

joint with respect to the stick, the frame, and the cover, the cover and frame being in section.

Figure 2 is a diagrammatic view of my umbrella showing the resilient joint in flexed position.

5 Figure 3 is a sectional view of the resilient universal joint of a hollow cylindrical umbrella stick in unflexed position.

Figure 4 is a sectional view of the resilient universal joint of a hollow cylindrical umbrella stick in flexed position.

10 Figure 5 is a sectional view of a modified resilient joint.

Figure 6 is a sectional view of a modified flexing member.

Figure 7 is a section taken on the line 7—7 of 15 Figure 6.

Referring to the drawing, I show an umbrella construction having a covering A, disposed over a flexible truss frame supported by a two element 20 stick or shaft, generally designated as B, the upper element being designated C and the lower element D, the elements C and D being united by a resilient universal joint E.

The covering A is disposed over the rib structure which is attached to the upper element of 25 the stick C, and to a runner sleeve 10 which fits closely or snugly on and is slidable along the stick B, for the purpose of opening and closing the umbrella.

The stick or shaft B is composed of the two 30 elements C and D, which are united by the universal self-aligning joint E, to provide an integral stick capable of being flexed at the joint E.

The hollow cylindrical element C of the stick has, at the end which joins the element D, a ball 35 portion 12, of the joint E, from which a cylindrical extension 14 projects. The ball portion 12 is supported in a socket bearing 16, of the hollow cylindrical element D of the stick. Attached to the inner periphery of the stick D, immediately 40 below the socket bearing, are a plurality of powerful restoring springs 18 equispaced about the inner periphery of D. The said springs 18 impinge upon the ball joint extension 14, to constrain the elements C and D of the stick in alignment under normal externally unstressed conditions.

45 The relative proportions of the ball joint extension 14 and the springs 18 are such that wedging of the said extension 14 between the springs 18, when the joint is flexed, will not occur. 50 The elements C and D of the stick do not fit flush, but are separated by a space to permit flexing at the joint E.

55 In the construction illustrated in Figure 5, a cylindrical flexing member 20 extends from the 55

ball portion 22 of the resilient universal joint E well downward into the hollow cylindrical stick element D.

The hardened annular ring guide 24 is fitted into the hollow cylindrical stick element D, and surrounds the lower end of the flexing member 20. This ring guide 24 acts as a support for the flexing member 20, the upper edge 25 acting as a fulcrum. The surface 26 of the ring guide 24 is cut back conically to provide freedom of sliding motion of the flexing member 20 when flexing.

When the bending moment at the joint E, is sufficiently great to bend the flexing member 20 into contact with the internal wall of the stick element D, additional resisting moment is encountered, yieldingly tending to prevent further joint flexure and limiting the flexing motion without shock.

For practical purposes the joint E, together with its extension member 20 can be made up of sections threaded together.

The ball portion 22 of element C has an upper screw-threaded extension 28, fitting into a plug 30, which in turn is fitted into the element C by means of screw threads.

The socket portion of the joint E is constructed of screw-threaded elements 32 and 34 having spherical concave surfaces.

A modification of my self-aligning universal joint for use in an umbrella stick is shown in Figures 6 and 7. In this modification the flexing member 36 is square in cross section, and the ring guide 38 is provided with a square aperture, so that relative axial rotation of the elements C and D of the joint is prevented. Although shown as square, the cross section of the flexing member extension 36 of the ball portion of the joint and the cooperating aperture in the ring guide disk may be of any polygonal shape. This modification is also capable of employment in a self-aligning power-transmission shaft to transmit energy from a rotating source to a rotatable energy utilizing device not in axial alignment therewith.

In this specification where I have used the term unflexed position of the universal joint, I mean that position wherein the sections of the shaft or stick connected by the joint are in axial alignment. Any other position of the sections of the shaft or stick will place the joint in a flexed position.

Furthermore, although my invention has been illustrated and described as applied to an umbrella stick to more adequately protect the bearer of the umbrella and to prevent the force of the wind turning the umbrella inside out, its use is not limited to that purpose, but may also be utilized for many other purposes as, for example, to measure the force of the wind.

My invention therefore is not to be restricted except insofar as is necessitated by the prior art and by the spirit of the appended claims.

I claim:

1. An umbrella comprising a stick on which a frame is mounted, a self-aligning universal joint in the stick, to permit the section of stick on which the frame is mounted to tilt relative to the remaining section of the stick and to align the two sections of the stick.

2. The combination of an umbrella and a stick, said stick being composed of two parts connected by a self-aligning universal joint located within the stick.

3. In a shaft, a self-aligning resilient universal

joint entirely within said shaft, said shaft having a uniform external cross-sectional shape so that closely fitting sleeves or collars may be readily passed along the shaft over said joint when in unflexed position.

4. In a universal joint having two joined elements, a self-aligning flexing member for said joint, said flexing member being circular in cross-section so that the joined elements may rotate with respect to each other about their respective axes.

5. An umbrella having a stick and a runner sleeve slideable thereon, a self-aligning universal joint associated with said stick, said runner sleeve being slideable along the stick over said joint when in unflexed position.

6. An umbrella having a two-part stick and a runner sleeve slideable thereon, a self-aligning universal joint connecting the parts of the stick, said runner sleeve slideable along the stick over said joint.

7. A wind-break having a covering and a stick and a self-aligning universal joint in the stick.

8. In a sectional umbrella shaft, a self-aligning universal joint and means to prevent relative rotation of the sections of the shaft.

9. A self-aligning universal joint connecting two elements and comprising a ball attached to one of said elements, a socket bearing attached to the other of said elements, a cylindrical extension projecting from the said ball in a direction away from the element to which the ball is attached, and a plurality of springs secured each at one end to the element to which the socket bearing is attached, said springs impinging upon said cylindrical extension.

10. In a self-aligning universal joint connecting two elements, a ball attached to one of said elements, a socket bearing attached to the other of said elements, a cylindrical flexing member affixed to and extending from said ball in a direction away from the element to which said ball is attached, and a guide secured to the element to which said socket bearing is attached, said flexing member interfitting with and being supported at its free end within said guide.

11. A self-aligning universal joint connecting two elements and comprising a ball attached to one of said elements, a cooperating socket bearing attached to the other of said elements, a flexing member of polygonal cross-section affixed to and extending from said ball in a direction away from the element to which said ball is attached, and a guide secured to the element to which said socket bearing is attached, said guide having a longitudinal opening substantially of the same shape and size as the cross-section of said flexing member, and said flexing member interfitting with and being supported at its free end within said guide.

12. In combination, a shaft comprising a plurality of sections, each of said sections having the same cross-sectional dimensions, a self-aligning universal joint connecting said sections whereby said sections are movable relative to each other into and out of axial alignment, and means snugly fitting and slideable on said sections from one to the other thereof when said sections are in axial alignment.

13. In combination, a shaft comprising a plurality of sections, each of said sections having the same cross-sectional dimensions, a self-aligning universal joint located entirely within and connecting said sections whereby said sections are movable relative to each other into and

- out of axial alignment, and means snugly fitting and slidable on said sections from one to the other thereof when said sections are in axial alignment.
- 5 14. In combination, a shaft, and a self-aligning universal joint entirely within said shaft.
15. In an umbrella, a stick comprising a pair of sections, said sections having a uniform outside diameter, a self-aligning universal joint located entirely within said stick and connecting said sections, and a runner sleeve mounted on said stick and adapted to be slid from one of said sections to the other.
- 10 16. An umbrella having a two-part stick and a runner sleeve slidable thereon, a self-aligning universal joint connecting the parts of said stick, said runner sleeve being slidable along said stick over said joint when in unflexed position.
- 15 17. In an umbrella a shaft having a plurality of sections movable relative to each other by the force of the wind.
- 20 18. In an umbrella, a protective covering, a support therefor, and means associated with said support and separate therefrom whereby the application of a force to the covering laterally
- 25 thereof will cause said covering to move with respect to said support.
19. In an umbrella, a protective covering and a support therefor, said covering and support being normally concentric, and means associated with said support and separate therefrom whereby the application of a force to the covering laterally thereof will cause said covering to assume a position of eccentricity with respect to said support.
- 5 20. In an umbrella, a protective covering having an overhanging portion and a support therefor, said cover and support being normally concentric, and means associated with said support and separate therefrom whereby, when a force is applied to said cover at said overhanging portion, said cover will be deflected to a position eccentric with respect to said support.
- 10 21. In an umbrella, a resilient universal joint in the stick, said joint being located in said stick so that it is above the center of gravity of the projection of the covering on a plane parallel to said stick.
- 15 20 25
